UNITED STATES PATENT OFFICE

2,667,051

COMBINED ASH RECEIVER AND COASTER
UNITPhillip J. Mesi and Stanley T. Ogorek, Chicago,
Ill., assignors to Totebrush, Inc., Chicago, Ill.,
a corporation of Illinois

Application March 23, 1951, Serial No. 217,234

2 Claims. (Cl. 65—53)

This invention relates to a combined ash receiver and coaster unit. Specifically it has reference to a unit which may be used by two or more persons as an ash tray and for supporting glasses of beverage.

When at the card table, for example, the players desire that the table top be as uncluttered as possible. Inevitably, with two or more ash trays in use, and liquid refreshment within convenient reach, the area available for use in the card game is substantially diminished. Moreover, a hazard and a nuisance is presented by glasses placed at random, and in positions where even a glancing blow may topple the glass and contents, with consequent breakage and soiling of carpets.

Individual coasters or trays for the glasses are in common use, but being light in weight are of little or no value in safeguarding the glasses against being toppled, since the coaster itself may readily slide on the table. In order to guard against this type of occurrence the player will place the glass away from his arms and hands toward the center of the table, thus interfering with the playing area.

Combined ash tray and coaster units are known, but have not included a feature whereby the component parts may be collapsed so as to occupy the least possible space when stored during periods of non-use.

This invention has for its principal object a combined ash receiver and coaster unit comprising a tray for the ashes and depressions for holding the lighted cigarettes or cigars, together with a pair of coasters hingedly mounted on the tray and adapted to be severally swung from a concealed position beneath the tray to an exposed position ready for use, the arrangement being such that one unit may accommodate two users.

Another object is to provide a unit as aforesaid in which the coasters are so constructed that when in concealed position the unit appears as a simple ash tray—not as a device having a dual utilitarian purpose and therefore non-esthetic.

A further object is to provide a unit as aforesaid which is so constructed that both coasters may be of identical configuration notwithstanding the mounting thereof at opposite sides of the ash tray.

Another object resides in the proportioning of the coasters and ash tray in relation to each other, such that the coasters are mutually abuttable, thus eliminating the need for full reliance

on separate stop members which, when made of plastic, may become broken in use.

Still another object is to provide a unit as aforesaid which comprises only a few relatively movable parts and may be easily washed without dismemberment.

In the drawing which shows one form in which the invention may be embodied:

Fig. 1 shows a top plan view of the unit with the coasters in exposed position;

Fig. 2 shows a top plan view of the same with the coasters in concealed position;

Fig. 3 is a front elevational view of the unit as shown in Fig. 2;

Fig. 4 is a cross-sectional view taken on the line 4—4 of Fig. 1; and

Fig. 5 is a cross-sectional view taken on the line 5—5 of Fig. 2.

The invention unit comprises an ash receiver in the form of a tray or body 10 of any suitable esthetic configuration, but shown exemplificatively as substantially polygonal and with curved faces. Inasmuch as a molded plastic composition lends itself well to an article as herein disclosed such material is preferred. Accordingly the body 10 will comprise a relatively thin walled structure as shown, including an upper, inwardly sloped outer wall portion 12 and a lower, vertical wall portion 13. Portions 14—14 representing thickened zones of the wall portion 12 are provided with recesses 15 for holding lighted cigarettes and as will be understood.

The lower wall portion 13 is interrupted in diagonally opposite regions to define a pair of openings 16—18 through which the coasters to be described may enter and emerge when swung from one position to the other.

A pair of enlarged knobs or embossments 21—21 is provided at diagonally opposite corners of the body 10, and each is tapped to receive a bolt or screw 22—22. The coasters 23—23 are in the form of swingable trays, having a substantially circular contour except at the regions denoted by numeral 24, whereat the same are delineated in such manner that when in concealed position the wall of the trays is in effect a continuation of the wall portion 13 of the body. Thus esthetic considerations are satisfied whenever the unit is functioning as a simple ash receiver, and as best depicted in Fig. 2.

The trays 23—23 are of identical size and shape for ease in manufacture, and are each provided with a cylindrical recess 26—26, the floor of which is grooved in concentrically circular manner or otherwise to define a plurality of lands

27 upon which the glass may rest without moisture condensing thereon causing adherence of the glass to the tray. Since the provision of an interrupted floor as just described is common in coaster construction there will be no elaboration thereof.

Each of the trays 23-23 is provided with a rounded projection 31-31 of the same diameter as the embossments 21-21 so that when the trays are in concealed position the exterior of the ash receiver presents a flush appearance insofar as the parts 21 and 31 are concerned. To facilitate moving the trays from one position to the other each is provided with a handle 32-32 so arranged that when the tray is swung to closed position the handle will overhang the adjacent edge of its recess 18, thus to limit the inward movement thereof, and also to insure that the exterior flush relationship of the co-planar walls of the coaster and ash receiver is maintained.

Additionally the several parts are so dimensioned that when the trays 23-23 are in closed position they abut at the center, thus insuring that one tray acts as a stop for the other. Consequently full reliance need not be placed upon the knobs 32-32 for limiting inward movement thereby lessening the chance of breakage of the knobs or of the wall 13 abutted thereby.

Moreover it will be noted that the bottom face of each tray 23-23 is co-planar with the bottom edge of the wall sections 13-13. Thus the trays are, at all times, fully supported on the table top, thereby relieving stress on the embossments 21-21 and 31-31 and consequent possible fracture thereof.

While we have shown a particular embodiment of my invention, it will be understood, of course, that we do not wish to be limited thereto since many modifications may be made, and we therefore contemplate by the appended claims to cover any such modifications as fall within the true spirit and scope of our invention.

Having thus described our invention, what we claim and desire to secure by Letters Patent is:

1. A combined ash receiver and coaster unit comprising a substantially elliptical body having an ash-receiving depression therein, and a pair of peripherally-spaced wall portions and openings extending downwardly from said body at the periphery thereof for spacing the floor of said depression above a supporting surface, a pair of diametrically-opposed coaster trays

pivotaly suspended from said body for swinging movement on individual vertical axes through said openings into and out of the space below said floor for concealment or for use respectively, said trays having a substantially circular periphery, the diameter whereof is substantially equal to half the major axis of the elliptical body, said vertical axes being disposed on a line passing through the center of the ellipse, the 10 said wall portions and the exterior portion of each said tray when in concealed position being co-planar with the periphery of said body.

2. A combined ash receiver and coaster unit comprising a substantially elliptical body having an ash-receiving depression therein, and interrupted wall portions extending downwardly from said body at the periphery thereof for spacing the floor of said depression above a supporting surface, a pair of diametrically-opposed coaster trays pivotally suspended from said body for swinging movement on individual vertical axes into and out of the space below said floor for concealment or for use respectively, said trays having a substantially circular periphery, the diameter whereof is substantially equal to half the major axis of the elliptical body, and a portion of each tray being conformed to the adjacent interrupted wall for flush relationship therewith when the tray is in concealed position, and a handle for each tray for abutment with the wall for limiting closing movement thereof independently of the position of the other tray.

PHILLIP J. MESI.
STANLEY T. OGOREK.
